UNITED STATES PATENT OFFICE.

STERLING ELLIOTT, OF NEWTON, MASSACHUSETTS.

APPARATUS FOR COATING SHEETS OF PAPER.

1,197,925.

Specification of Letters Patent. Patented Sept. 12, 1916.

Application filed December 28, 1914. Serial No. 879,281.

To all whom it may concern:

Be it known that I, STERLING ELLIOTT, a citizen of the United States, residing at Newton, in the county of Middlesex and 5 State of Massachusetts, have invented an Improvement in Apparatus for Coating Sheets of Paper, of which the following is a specification.

In the manufacture of stencil-sheets for mimeograph work and the like, it is customary to coat the paper with a waterproof composition or substance of some sort. This composition is in liquid form when applied to the sheets of paper and is subsequently 10 solidified. It is very difficult to apply the composition in liquid form to a sheet of paper, so that when solidified a layer of uniform thickness extends over the entire sheet.

This invention has for its object a novel 20 process of coating sheets of paper with a liquid composition, which when solidified will form a layer of uniform thickness over the entire sheet; and the invention also involves the construction of apparatus especially 25 adapted for carrying out my process in a convenient and expeditious manner.

My process consists in submerging the sheets of paper in a liquid coating composition and then drawing the sheets therefrom 30 at a rate of speed corresponding approximately to, but preferably slower than the rate of flow of the liquid coating composition on the surfaces of the sheets, if such flow was permitted, thereby to prevent the 35 flowing of said liquid coating composition on the surfaces of the sheets. When the sheets are thus coated and the coating is allowed to dry, layers of uniform thickness cover both surfaces of the sheets.

40 The apparatus which may be employed for carrying out my invention comprises movable supporting-means for a plurality of sheets by which they are held above a receptacle containing the liquid coating composition, and means for lowering said supporting-means, thereby to submerge the sheets in the composition, movement of which may be at any desired rate of speed, and for subsequently raising said supporting-means at a relatively slow rate of speed. The sheets are provided with detachable 45 hangers arranged for removable engagement with said supporting-means by which the sheets are suspended therefrom, and to insure the sheets being held in flat form, 50 weights are arranged at their lower ends,

which weights as well as the hangers are made co-extensive with the width of the sheets; and furthermore the weights and hangers are provided with laterally extended means arranged for engagement with corresponding laterally extended means on adjacent weights and hangers to prevent the sheets from touching each other even if they should swing to and fro. 60

The apparatus also embodies a temporary support for a plurality of sheets, which is arranged in front of the supporting-means on which the sheets are separately placed by hand, to correspond with marks on the support so that they will be spaced apart sufficiently to prevent them from touching each other. Said temporary support and said supporting-means are both so constructed as to admit of a sliding movement 70 of the sheet-hangers thereon, so that the sheets may be moved from the temporary support onto the supporting-means. 75

The apparatus also embodies moving-means arranged to move a plurality of 80 sheets from the temporary support onto the supporting-means, in spaced-apart relation, said moving-means also being arranged for moving a plurality of sheets from the supporting-means onto a carrier, still maintaining their spaced-apart relation. Said carrier is made portable and is removably arranged on the frame in rear of the supporting-means and is made long enough to receive one or more sets of sheets which are 85 moved from the supporting-means, and in case a carrier is employed which is arranged for holding more than one set of sheets, the moving-means will be arranged for moving a plurality of sheets along on the carrier, 90 still maintaining their spaced-apart relation thereby to vacate a space sufficient to receive a plurality of sheets from the supporting-means. The carrier is made removable, so that it, together with the sheets carried by it, may be taken from the apparatus and placed in a suitable rack, where the sheets are permitted to dry, the liquid coating composition thereon becoming solidified. A large number of carriers are therefore 95 used in connection with the apparatus. 100

The apparatus also embodies power-driving means for the supporting-means by which it is moved downward and upward, and said driving-means is arranged to move 110 said supporting-means downward at a fast rate of speed, and upward at a slow rate of

speed, and reversing clutch-mechanism is employed which is arranged for controlling the connection of the power-driving means with the supporting-means. Said reversing clutch-mechanism has a clutch-lever for controlling its operation and controlling-means are provided for said clutch-lever by which its movement in a direction to cause downward movement of the supporting-means is controlled, and said controlling-means is associated with and arranged for operation by the moving-means, so that the clutch-lever will be prevented from movement, as aforesaid, except when said moving-means is in its elevated position, in which position it is disengaged from the sheets. Thus the supporting-means can be moved only when the relative positions of the elements associated with each other are properly disposed. In view of the fact that the movement of the supporting-means in a downward direction may be as rapid as desired, the clutch-lever may be moved and held manually for the accomplishment of this result, as it requires but a short period of time, but as it requires a long period of time for the supporting-means to complete its upward movement, it is irksome to hold the clutch-lever during such period, hence locking-means are provided for engaging the clutch-lever when moved into position to cause upward movement of the supporting-means, by which said lever is held during such period of time; and means arranged for actuation by the supporting-means, when completing its upward movement, are provided for restoring said locking-means to its normal or disengaging position at such time.

Figure 1 is a front elevation of an apparatus for coating sheets of paper embodying this invention. Fig. 2 is a left-hand elevation of the apparatus shown in Fig. 1. Fig. 3 is an enlarged plan view of the apparatus shown in Fig. 1. Fig. 4 is a front elevation of the means for conveying the sheets of paper from one to another part of the apparatus. Fig. 5 is a transverse vertical section of the carrier. Fig. 6 is a longitudinal vertical section of the apparatus taken through the receptacle containing the liquid coating composition. Figs. 7 and 8 are detail views of the means for raising and lowering the supporting-means for the sheets. Figs. 9 and 10 are detail views of one of the sheets with hanger and weight thereon. Figs. 11 and 12 are detail views of controlling-means and locking-means for the clutch-lever. Fig. 13 is a detail view of one of the normally flexed strips, which is arranged in the bars of the moving-means.

1 represents the receptacle which is intended to contain the liquid coating composition which is to be applied to the sheets of paper. It is of any suitable size and dimensions, and has a chute 2, at one end, arranged

near the top through which the coating composition is delivered to it; and has heating-means associated with it for heating the coating composition. The heating-means here shown, see Fig. 2, consists of a set or coil of pipes 3, arranged in the receptacle, at the bottom, which is connected with a hot-water heating apparatus 4, which latter may be of any well known or suitable construction. The receptacle is or may be open at the top.

Supporting-means for a plurality of sheets of paper is arranged above the top of the receptacle and is movable up and down, and upon downward movement the sheets of paper are submerged in the coating composition contained in the receptacle and upon upward movement the sheets are withdrawn. Said supporting-means, as here shown, consists of a rigid structure comprising a pair of side-bars 5, 6, arranged horizontally and in parallel relation and spaced apart a distance corresponding to the width of the receptacle, and rigidly secured to the lower ends of upright braces 7, 8, 9, 10, 90 which braces are attached at their upper ends to the end-portions of a horizontal cross-bar 12. The ends of said cross-bar 12 are fitted to slide in vertical guideways formed in upright posts 13, 14, arranged on the main frame-work. Said side-bars 5, 6, have brackets 15, at each end, with outstanding ears 16, arranged in vertical planes, which ears are fitted to slide in vertical guideways formed in upright posts 17, there being four such posts arranged at the four corners of the receptacle. Said side-bars 5, 6, each have plates arranged on their under sides, the edges of which extend beyond the sides of the bars, to form rabbets to receive engaging-portions formed on hangers, which are temporarily attached to the sheets and to permit of a sliding movement of said hangers and the sheets borne by them along from end to end thereof.

Referring to Figs. 9 and 10, wherein one of the sheets of paper 20 is shown, a hanger is attached to its upper edge by which it is arranged for suspension on said supporting-means, and a weight is attached to its lower edge by which to hold the sheet taut. The hanger is arranged for detachable connection with the sheets, and, as here shown, consists of a pair of angle-bars 21, 21, made longer than the width of the sheet, so as to extend throughout the width of the sheet and to project therefrom at each side, said projecting end-portions forming engaging-portions which engage the side-bars 5, 6; and said angle-bars are made long enough to extend from one to the other side-bar 5, 6, so that it may be arranged with its engaging-portions in engagement with both of said bars and thereby support the sheet between them. These angle-bars are arranged at op-

posite sides of the sheet with their corresponding flat faces adjacent each other and in engagement with the sheet, and they are held in such position by detachable means here shown as nippers.

- 22 represents one of the nippers, of which there may be two or more, as may be required. The nippers may be of any well-known spring-actuated type for easy manipulation, having their jaws arranged for engagement with the angle-bars, and by clasping said bars to hold them in engagement with the sheet and thereby to hold the sheet between them.
- 15 The sheet of paper is very thin, but it is held straight, at its upper edge, by the hanger, particularly as the hanger is co-extensive with the width of the sheet. As the angle-bars are arranged with flat faces 20 against the paper, the other arms or portions of said bars extend laterally in opposite ways, and said portions, by engaging corresponding portions of adjacent hangers, act to hold the upper end-portions of the sheets 25 free from contact with each other, thus preventing them from sticking together. On account of the tendency of the sheet to flex or curl, a weight is employed at its lower end, which weight is also arranged 30 to hold the lower edge of the sheet straight, so that the sheet will be held in flat form over all. As a simple form of weight which may be easily and quickly applied by a machine, if desired, a sheet metal clip 23 is here 35 shown, which is made as long as or longer than the width of the sheet, thereby to engage it throughout its entire width. This clip consists of a strip of sheet metal bent U-shaped to embrace the edge of the sheet and 40 to admit of its being flattened for engagement with the sheet by pressure upon it throughout its length or at intervals as desired. This form of clip may be subsequently detached from the sheet easily and 45 quickly, by securing it from the sheet. Said clip has ears 24, at or near each end, which extend laterally a short distance, which, when the sheets are suspended from the supporting-means, will occupy positions to 50 strike against the corresponding ears of adjacent clips, or it may be the clips themselves, in case the sheets should swing from their points of suspension, thereby preventing the sheets from touching each other and 55 sticking together. It is of considerable importance that some means shall be employed to prevent the sheets from sticking together in case they should move or swing, and the laterally extended portions of the hanger, 60 and the ears on the weight are effective and easy to construct.

The sheets, when thus prepared, by the application thereto of the hangers and clips, are ready to be placed on the movable supporting-means, and, herein means are pro-

vided for arranging them on a stationary support, temporarily, which support is arranged in front of the supporting-means, so that a large number may be moved at one operation onto the movable supporting- 70

means, a number sufficient to completely fill said movable supporting-means. Said stationary support, as here shown, consists of a pair of horizontally arranged bars 25, 26, arranged on the frame in front of the movable supporting-means and so disposed with relation thereto that the supporting-means may be moved to bring its side-bars 5, 6, into alining position therewith, and said stationary bars 25, 26, have rabbets on their adjacent faces to receive the engaging-portions of the hangers bearing the sheets, so that the sheets may, by a sliding movement, be conveyed from said stationary bars to the side-bars of the movable supporting-means. 85 In Fig. 3 one sheet only is represented as supported on the stationary bars for illustration.

To facilitate sliding the sheets from the stationary support to the side-bars of the movable supporting-means, the adjacent ends of the bars are rabbeted, so that the end-portions of the bars may extend over each other, and upon referring to Fig. 3, the end-portions 18 on the side-bars of the supporting-means are here shown as having their top faces curved downward, thereby obviating a shoulder at the meeting points of the bars. The end-portions 18, extend over the tops of the end-walls of the receptacle 1, and may strike against said walls or adjustable stops thereon upon downward movement of the supporting-means, thereby to limit such movement. Means are herein provided for moving the sheets, reposing on the stationary support temporarily, as a set or series, into engagement with the movable supporting-means, and to regularly space apart the several sheets, and said means is also employed to move them from the supporting-means onto a portable-carrier in spaced-apart relation, by which they may be taken from the machine. Said means, as here shown, comprises a pair of long slender bars 30, 31, slidably supported intermediate 115 their length and arranged in parallel relation at opposite sides of the machine. These bars are here shown as hollow and quadrilateral in cross-section, aiming to make them as stiff as possible; and to increase their 120 stiffness on account of said bars having a tendency to sag at their ends when supported only intermediate their length, a brace-bar 32 is arranged within and extended throughout the length of each bar, which 125 brace-bars are made with a decided curve throughout their length, as represented in Fig. 13, so that when driven into or arranged in the hollow-bars, they will have a tendency to resist the sagging tendency of 130

the unsupported end-portions of said bars. Said bars 30, 31, have rack-teeth 34, arranged along their upper sides for a portion of their length, for engagement therewith of pinions 35, which are secured to a shaft 36, to which a hand-crank 37 is connected, by which it may be rotated. Said bars have arranged along their undersides a series of downwardly extended teeth or pins 38, which are spaced apart, corresponding to the distance it is proposed to space apart the sheets when suspended from the supporting-means. These bars 30, 31, which are moved longitudinally by rotation of the hand-crank 37, are also adapted to be moved up and down, in any position they may occupy, and to this end the frame which slidably supports said bars, is arranged for movement up and down. Said frame comprises a horizontal transversely arranged cross-bar 40, having at each end a bar 41, arranged at right-angles thereto, and said bars 41, each bear blocks 42, at each end, in which said bars 30, 31, slide, and said frame has a vertical center-screw 43, rising from it which extends through an upright bearing 44, on a frame-bar 45, which is arranged transversely with respect to the machine, and is secured at its ends to opposite sides thereof. Said screw has arranged on it a nut 46, having a bevel-gear 47, fast to it, which rests on top of said upright bearing 44, so that the turning of said gear and nut causes said screw to move longitudinally up or down according to the direction said gear is turned, with a corresponding up and down movement of the bearing-frame for the bars 30, 31. Said bevel-gear is engaged by a bevel-gear 48, secured to a shaft 49, having its bearing in the frame-bar 45, and a hand-crank 50, is secured to said shaft for rotating it. When it is desired to move the bars 30, 31, longitudinally, the hand-crank 37, is rotated, and when it is desired to raise or lower said bars, the hand-crank 50, is rotated. Assuming a set of sheets to be reposing temporarily on the stationary support preparatory to being moved onto the movable supporting-means, and another set 50 of sheets to be held by said supporting-means, and it is desired to shift the sets of sheets, the bars 30, 31, will be raised high enough for their pins 38 to escape the tops of the sheet-hangers, and then they will be moved in a direction toward the left, Fig. 3, until the left-hand end-portions thereof occupy positions above the sheets reposing on the temporary support; then said bars are lowered and the teeth 38 caused to enter the spaces between the sheets on said support and also to enter the spaces between the sheets on the supporting-means; then said bars are moved in a direction toward the right and all of the sheets engaged by 65 them will be moved along from the posi-

tions they occupy, those on the temporary support being moved onto the supporting-means, and those on the supporting-means being moved onto the portable-carrier; then said bars are raised to disengage the sheets 70 and thus caused to occupy their normal elevated positions.

The portable-carrier, here shown, is a simple structure arranged on the machine-frame comprising a pair of rabbeted side-bars 56, 56', arranged in parallel relation and spaced apart a distance corresponding to the distance between the side-bars of the supporting-means, and cross-bars 57, 57', see Figs. 3 and 5, rigidly connected at their ends 80 to said side-bars, thus forming a rigid structure. The side-bars of the machine-frame are arranged to receive and support said portable-carrier, and to hold it in fixed relation with the side-bars thereof, in alinement with the stationary-bars 25, 26, so that when the supporting-means occupies a predetermined position with respect thereto, the side-bars of the stationary-support and the supporting-means and the portable-carrier, all will be arranged in alinement, and thus admit of a sliding movement of the sheets from one to another. The portable-carrier may be made long enough to contain more than one set of sheets from the 95 supporting-means, if desired, and is here shown as made long enough to hold two sets, and in such case the shifting or moving-means for the sheets will be arranged with downwardly extended pins to engage the 100 first set of sheets which is moved onto the portable-carrier, and to move them along on the carrier to admit of another set being moved thereon from the supporting-means. Said carrier may be removed from the machine by sliding it endwise, and to prevent such movement, when not required, turn-buttons 58 or some equivalent means are provided which are arranged on the end of the machine-frame and adjusted to a position to obstruct endwise movement of the carrier.

While the sheets are reposing on the movable supporting-means, said means is operated to lower the sheets into the receptacle 115 1, thereby submerging them in the coating substance or composition contained therein, and subsequently to raise them, and the means here shown for thus moving said supporting-means is further arranged to move 120 said means in a downward direction at a relatively fast rate of speed, and in an upward direction at a relatively slow rate of speed. The means here shown for accomplishing this result will now be described.

60 represents a cord which is attached at one end to an eye 61, arranged on the cross-bar 12, and said cord passes over a pulley 62, which is supported at the top of the frame above the cross-bar, and also over a 125 130

pulley 63 supported on a bracket arranged on said frame and thence down and around a drum 64, which is connected with a reversible power-driving mechanism, by which 5 said drum may be rotated in either direction at will. Said drum is secured to a shaft bearing a spur-gear 65, which engages a pinion 66, secured to a shaft bearing a spur-gear 67, which engages a pinion 68, secured to a shaft bearing a spur-gear 69, which engages a pinion 70, secured to a shaft 71. Said shaft 71 has mounted on it two friction-clutches arranged respectively for forward and reverse drive.

15 75 represents one of the clutch-members which is splined on the shaft for sliding movement into and out of engagement with the friction-face of a pulley 76, which is loosely mounted on the shaft; and 77 represents the other clutch-member which is likewise splined on the shaft 71, for sliding movement into and out of engagement with the friction-face of the pulley 78, likewise loosely mounted on the shaft. Slidably arranged on the shaft, between said clutch-members, is the clutch-actuating means consisting, as here shown, of sliding-sleeves 80, 81, 82, arranged side by side, with the end-most members 80, 81, having their outer 20 ends or faces provided with ball-bearings for engagement with the adjacent ends of the clutch-members 75 and 77, and the member 82, which is arranged between said members 80 and 81, having a circumferential 25 groove to receive inwardly extended pins on a yoke 84, secured to a pivot-shaft 85, and having an arm 86 extended from it, which is connected by a link 87, with an arm 88, secured to a shaft 89, to which shaft the clutch-operating lever 90, is secured. Movement of said lever 90, in one direction, operates one of the clutch-members, and in the other direction operates the other clutch-member. The pulley 76, has arranged on it 30 a belt 91, which passes around a pulley 92 on the shaft of an electric-motor 93, and the pulley 78 has a cross-belt 94, which passes around a pulley 95, on the shaft of said motor. The pulley 78 when driven is designed 35 to turn the shaft 71 in a direction to lower the supporting-means, and the pulley 76, when driven, is designed to turn said shaft 71 in a direction to raise the supporting-means, and by reference to Fig. 1, the driving-pulleys on the motor being of different diameter, causes the pulleys 76 and 78 to turn the shaft 71, respectively, at different rates of speed, so that the supporting-means may be lowered at a relatively fast rate of 40 speed and may be raised at a relatively slow rate of speed. This enables the sheets to be quickly submerged in the coating composition and to be withdrawn from said composition slowly or at a speed approximately 45 equal to or less than the flow of the compo-

sition on the surfaces of the sheets, thereby preventing such flow, and resulting in a uniform coating being applied to the sheets.

When moving the clutch-lever 90 in a direction to operate the clutch and move the supporting-means for the sheets downward, it is quite necessary that the moving or shifting-means for the sheets shall be in its normal elevated position, otherwise said moving-means will not operate properly, 75 and there is liability of breakage of the parts, and herein controlling-means are provided for said clutch-lever by which it may be moved in such direction only when the moving-means is in its elevated position. 80 Furthermore, when moving the clutch-lever in the direction to operate the clutch to move the supporting-means for the sheets upward on account of such movement of the supporting-means being very slow, it is 85 desirable to automatically lock the clutch-lever in such position, so that such slow movement may continue without the necessity of the operator holding the clutch-lever, and that such locking-means shall be 90 arranged to be operated to disengage the clutch-lever at the end of the upward movement of the supporting-means. Hence, locking-means are also provided for the clutch-lever arranged for operation in the 95 manner set forth. Said controlling-means and locking-means for the clutch-lever are shown in detail in Figs. 11 and 12.

96 represents an arm pivoted to one of the uprights on the frame having a laterally 100 extended arm 97, with or without a roll thereon, arranged to rest continually upon one of the side-bars of the moving-means, so that said arm is moved on its pivot by the moving-means as the latter rises, and 105 falls, and said arm 96 has another extension-piece 98, which extends in a direction opposite to that of the arm 97, having an angularly formed end-portion, and said extension-piece 98 is movable by the arm bearing 110 it, into and out of the path of movement of the clutch-lever 90, and at a particular part of said path, so that when in its lowermost position, said clutch-lever will strike it, if moved inwardly during the time it is in such 115 lowermost position, but when in its elevated position, said lever 90 may be moved freely. As the position of said arm 96, is controlled by the moving-means it will be observed 120 that it may be employed to control the movement of the clutch-lever in a direction to operate the clutch to move the supporting-means for the sheets in a downward direction.

As a locking-means for the clutch-lever, 125 a gravity latch-lever 100, is pivoted to an upright on the frame, the latch-formed end of which is adapted to engage a pin 101, projecting laterally from the clutch-lever, when the clutch-lever is moved upward and 130

into position to operate the clutch and to move the supporting-means for the sheets in an upward direction. Said latch-lever normally rests by gravity on the pin 101, 5 of the clutch-lever, with the pin at an intermediate point on the latch-lever remote from its latch-formed end-portion and movement of the clutch-lever is permitted as the pin 101, is free to move along on the 10 underside of said latch-lever, but when said clutch-lever is moved outward, its pin 101 will be moved into engagement with the latch-lever and the clutch-lever will then be held. Said latch-lever has a rearward ex- 15 tension 102, which is arranged beneath one end of a lever 103, pivoted at 104, and the other end of said lever 103, has a pin 105, extended laterally from it with or without a roll thereon, which is arranged in the path 20 of movement of the supporting-means, as, for instance, one of the side-bars thereof, so that when the supporting-means arrives at the upper end of its stroke, it will engage and lift said pin 105, and thereby move the 25 lever 103, to cause its end opposite said pin to move downwardly and engage and move downwardly the rear end-portion of the latch-lever, and thus lift said latch-lever and disengage the clutch-lever. The locking 30 of the clutch-lever at the beginning of the up-stroke of the supporting-means, and the unlocking of said lever at the end of said up-stroke, is thus automatic.

It is apparent that many of the structural features here shown and described 35 may be changed without departing from the spirit and scope of my invention; therefore, I desire it to be understood that the structure here shown is illustrative, and not 40 restrictive.

I claim:—

1. In an apparatus for coating sheets of paper, the combination of a receptacle 45 adapted to contain a liquid coating composition, movable supporting-means for a plurality of sheets arranged above said receptacle, means to move said supporting-means downward and upward to submerge the sheets in and then withdraw them from 50 said coating composition, a temporary support adapted to receive upon it a plurality of sheets, arranged in front of said movable supporting-means, and means for moving a plurality of sheets from said temporary support 55 onto the supporting-means.

2. In an apparatus for coating sheets of paper, the combination of a receptacle 60 adapted to contain a liquid coating composition, movable supporting-means for a plurality of sheets arranged above said receptacle, means to move said supporting-means downward and upward to submerge the sheets in and then withdraw them from 65 said coating composition, a pair of stationary side-bars arranged in parallel relation

in front of said movable supporting-means adapted to receive upon them a plurality of sheets, and means to move a plurality of sheets from said side-bars onto the supporting-means.

3. In an apparatus for coating sheets of paper, the combination of a receptacle 70 adapted to contain a liquid coating composition, a pair of side-bars arranged horizontally above said receptacle in parallel 75 relation and rigidly connected together, said bars adapted to receive upon them a plurality of sheets, and means to move said rigidly connected bars downward and upward, a temporary support arranged in front 80 of said side-bars adapted to receive a plurality of sheets, and means to move a plurality of sheets from said temporary support onto said side-bars.

4. In an apparatus for coating sheets of 85 paper, the combination of a receptacle adapted to contain a liquid coating composition, movable supporting-means for a plurality of sheets arranged above said receptacle, means to move said supporting-means downward and upward to submerge the sheets in and then withdraw them from 90 said coating composition, a temporary support adapted to receive upon it a plurality of sheets, arranged in front of said movable 95 supporting-means, and means for moving a plurality of sheets from said temporary support onto the supporting-means in spaced-apart relation.

5. In an apparatus for coating sheets of 100 paper, the combination of a receptacle adapted to contain a liquid coating composition, movable supporting-means for a plurality of sheets arranged above said receptacle, means to move said supporting-means downward and upward to submerge the sheets in and then withdraw them from 105 said coating composition, a temporary support adapted to receive upon it a plurality of sheets, arranged in front of said movable 110 supporting-means, bars having downwardly extended pins regularly spaced apart, and means for moving said bars to engage a plurality of sheets on the temporary support and move them onto the movable supporting-means.

6. In an apparatus for coating sheets of paper, the combination of a receptacle 115 adapted to contain a liquid coating composition, movable supporting-means for a 120 plurality of sheets arranged above said receptacle, means to move said supporting-means downward and upward to submerge the sheets in and then withdraw them from 125 said coating composition, a temporary support adapted to receive upon it a plurality of sheets arranged in front of said movable supporting-means, bars having downwardly extended pins regularly spaced apart, a frame slidably supporting said bars, means 130

for moving the bars with relation to the frame, and means for moving the frame, thereby to cause the bars to engage a plurality of sheets on the temporary support 5 and move them onto the movable supporting-means.

7. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from 10 said coating composition, a temporary support adapted to receive upon it a plurality of sheets arranged in front of said movable supporting-means, a portable carrier arranged in rear of said supporting-means, and means for moving a plurality of sheets 15 from said temporary support onto the movable supporting-means and for moving a plurality of sheets from the movable supporting-means onto the carrier.

25. 8. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a temporary support adapted to receive upon a plurality of 30 sheets, arranged in front of said movable supporting-means, a portable carrier arranged in rear of said movable supporting-means, and means for moving a plurality of sheets from said temporary support onto the 35 movable supporting-means and for moving a plurality of sheets from the movable supporting-means onto the carrier, and also for moving a plurality of sheets along on the carrier to vacate a space to receive a plurality of sheets from the movable supporting-means.

40. 9. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said 45 coating composition, a temporary support adapted to receive upon it a plurality of sheets arranged in front of said movable supporting-means, means arranged in rear of said movable supporting-means to receive a plurality of sheets, and means for moving a plurality of sheets from said temporary support onto the movable supporting-means, and for moving a plurality of sheets from the movable supporting-means onto said 55 means arranged in rear thereof.

10. In an apparatus for coating sheets of paper, the combination of a receptacle adapted to contain a liquid composition, movable supporting-means for a plurality of sheets arranged above said receptacle, 70 means to move said supporting-means downward and upward to submerge the sheets in and then withdraw them from said coating composition, a temporary support adapted to receive upon it a plurality of sheets arranged in front of said movable supporting-means, means arranged in rear of said movable supporting-means to receive a plurality of sheets, and means for moving a plurality of sheets from said temporary support onto the movable supporting-means, and for moving a plurality of sheets from the movable supporting-means arranged in rear thereof, and for moving a plurality of sheets along on said 75 means in rear of the movable supporting-means to vacate a space to receive a plurality of sheets from the movable supporting-means.

11. In an apparatus for coating sheets of 80 paper, the combination of a receptacle adapted to contain a liquid coating composition, movable supporting-means for a plurality of sheets arranged above said receptacle, means to move said supporting-means 85 downward and upward to submerge the sheets in and then withdraw them from said coating composition, means arranged in rear of said movable supporting-means to receive a plurality of sheets, and means to move a plurality of sheets from the movable supporting-means onto said means arranged in rear thereof.

12. In an apparatus for coating sheets of 90 paper, the combination of a receptacle 105 adapted to contain a liquid coating composition, movable supporting-means for a plurality of sheets, arranged above said receptacle, means to move said supporting-means downward and upward to submerge the sheets in and then withdraw them from said coating composition, means arranged in rear of said movable supporting-means to receive a plurality of sheets, and means to move a plurality of sheets from the movable 110 supporting-means onto said means, and to move a plurality of sheets along on said means to vacate a space to receive a plurality of sheets from the movable supporting-means in rear thereof.

13. In an apparatus for coating sheets of 115 paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a portable-carrier arranged in rear of said movable supporting- 120 means.

means to receive a plurality of sheets, and means to move a plurality of sheets from the movable supporting-means onto said carrier.

14. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a portable-carrier arranged in rear of said movable supporting-means to receive a plurality of sheets, and means to move a plurality of sheets from the movable supporting-means onto said carrier, and to move a plurality of sheets along on said carrier to vacate a space to receive a plurality of sheets from the movable supporting-means.

15. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a temporary support adapted to receive upon it a plurality of sheets arranged in front of said supporting-means, a portable-carrier arranged in rear of said supporting-means, and means for moving a plurality of sheets from said temporary support onto the supporting-means in spaced-apart relation, and for moving a plurality of sheets from the supporting-means onto the carrier in spaced-apart relation.

16. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a temporary support adapted to receive upon it a plurality of sheets arranged in front of said supporting-means, a portable-carrier arranged in rear of said supporting-means, and means for moving a plurality of sheets from said temporary support onto the supporting-means in spaced-apart relation, and for moving a plurality of sheets from the supporting-means onto the carrier in spaced-apart relation, and for moving said sheets along on the carrier in spaced-apart relation.

17. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in

and then withdraw them from the coating composition, a temporary support adapted to receive upon it a plurality of sheets arranged in front of said supporting-means, means arranged in rear of said supporting-means to receive a plurality of sheets, and means for moving a plurality of sheets from said temporary support onto the supporting-means in spaced-apart relation, and for moving a plurality of sheets from the supporting-means onto said means in rear thereof in spaced-apart relation. 70 75

18. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a temporary support adapted to receive upon it a plurality of sheets arranged in front of said supporting-means, means arranged in rear of said supporting-means to receive a plurality of sheets, and means for moving a plurality of sheets from said temporary support onto the supporting-means in spaced-apart relation, and for moving a plurality of sheets from the supporting-means onto said means in rear thereof in spaced-apart relation, and for moving the plurality of sheets along on said means in rear of the supporting-means in spaced-apart relation to vacate a space to receive a plurality of sheets from the supporting-means. 85 90 95 100

19. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, means arranged in rear of said supporting-means to receive a plurality of sheets, and means to move a plurality of sheets from the supporting-means onto said means in rear thereof in spaced-apart relation. 105 110 115

20. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, means arranged in rear of said supporting-means to receive a plurality of sheets, and means to move a plurality of sheets from the supporting-means onto said means in rear thereof in spaced-apart relation, and to move a plurality of sheets along on said means in rear thereof in spaced- 120 125 130

apart relation to vacate a space to receive a plurality of sheets from the supporting-means.

21. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a portable-carrier arranged in rear of said supporting-means to receive a plurality of sheets, and means to move a plurality of sheets from the supporting-means onto said carrier in spaced-apart relation.

22. In an apparatus for coating sheets of paper, the combination of a receptacle adapted to contain a liquid coating composition, movable supporting-means for a plurality of sheets arranged above said receptacle, means to move said supporting-means downward and upward to submerge the sheets in and then withdraw them from said coating composition, a portable-carrier arranged in rear of said supporting-means to receive a plurality of sheets, and means to move a plurality of sheets from the supporting-means onto said carrier in spaced-apart relation, and to move a plurality of sheets along on said carrier, to vacate a space to receive a plurality of sheets from the supporting-means.

23. In an apparatus for coating sheets of paper, the combination of a receptacle adapted to contain a liquid coating composition, supporting-means for a plurality of sheets, means to hold said supporting-means above said receptacle which admits of a downward and upward movement thereof, power-driving means for the supporting-means having a control-lever, locking-means for said control-lever arranged to automatically lock said lever in one position, and to be moved by the supporting-means when arriving at the upper end of its stroke into another position to disengage the supporting-means.

24. In an apparatus for coating sheets of paper, the combination of a receptacle adapted to contain a liquid coating composition, supporting-means for a plurality of sheets, means to hold said supporting-means above said receptacle which admits of a downward and upward movement thereof, power-driving means for the supporting-means having a control-lever, a latch-lever arranged to move by gravity to disengage said control-lever and lock it in one position, and means operated by the supporting-means when arriving at the upper end of its stroke for lifting said latch-lever to disengage said control-lever.

25. In an apparatus for coating sheets of paper, the combination of a receptacle adapted to contain a liquid coating composition, supporting-means for a plurality of sheets, means to hold said supporting-means above said receptacle which admits of a downward and upward movement thereof, power-driving means for the supporting-means having a control-lever, arranged to move said supporting-means in a downward direction at a rapid rate of speed, and to move it upward at a slow rate of speed, and locking-means for said control-lever arranged to engage it when in one position and arranged to be operated by the supporting-means when the latter arrives at the upper end of its stroke to disengage said control-lever.

26. In an apparatus for coating sheets of paper, the combination of a receptacle adapted to contain a liquid coating composition, supporting-means for a plurality of sheets, means to hold said supporting-means above said receptacle which admits of a downward and upward movement thereof, reversing power-driving means for said supporting-means having a reversing-lever, and locking-means arranged to engage said lever when in one position and to be disengaged therefrom by the supporting-means when the latter arrives at the upper end of its stroke.

27. In an apparatus for coating sheets of paper, the combination of a receptacle adapted to contain a liquid coating composition, supporting-means for a plurality of sheets, means to hold said supporting-means above said receptacle which admits of a downward and upward movement thereof, moving-means arranged to move a plurality of sheets from the supporting-means, power-driving means for said supporting-means having a control-lever, and means arranged for movement by the moving-means to obstruct the path of movement of said control-lever in one direction when the moving-means is in a predetermined relative position.

28. A detachable hanger for a sheet of paper made co-extensive with the width of the sheet, and having outstanding end-portions, said hanger comprising a pair of angle-bars, and spring-clips engaging said bars to hold them in engaging-position on the sheet.

29. A detachable weight for the lower end of a sheet of paper consisting of a strip bent to embrace the edge of the sheet and having lateral projections.

In testimony whereof, I have signed my name to this specification, in the presence of two subscribing witnesses.

STERLING ELLIOTT.
